Primary Examiner — Melanie H Tung*Assistant Examiner* — Bao-Yen Nguyen*(74) Attorney, Agent, or Firm* — Cantor Colburn LLP(57) **CLAIM**

We claim the ornamental design for a display screen or portion thereof with graphical user interface, as shown and described.

DESCRIPTION

The FIGURE is a front view of a display screen or portion thereof with graphical user interface showing our new design.

The dot-dash lines show the display screen or portion thereof that form no part of the claimed design. The dash-dash broken lines show portions of the graphical user interface that form no part of the claimed design.
